UNITED STATES PATENT OFFICE

171,865

DESK TRAY

Leo J. Roth, Los Angeles, Calif.

Application October 26, 1953, Serial No. 27,322

Term of patent 3½ years

(Cl. D74—1)

To all whom it may concern:

Be it known that I, Leo J. Roth, a citizen of the United States, residing in Los Angeles, California, have invented a new, original, and ornamental Design for a Desk Tray, of which the following is a specification, reference being had to the accompanying drawing, forming part thereof:

Fig. 1 is a perspective view of a desk tray showing my new design.

Fig. 2 is a slightly enlarged cross-sectional view thereof.

I claim:

The ornamental design for a desk tray, substantially as shown.

LEO J. ROTH.
